UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

SINKER FED HOSIERY MACHINE.

Application filed July 26, 1923, Serial No. 653,960. Renewed March 19, 1926.

The invention concerns more particularly hosiery knitting machines in which, when heel and toe work is being done, the instep needles are elevated to idle position.

One object of the present invention is to employ measuring sinkers to cooperate with the needles to measure loop lengths of the yarn fed thereto, and the invention includes means whereby, when these needles are elevated to their idle plane, they will also assume a position at their upper portions inside of the normal needle circle, and thus out of range of the measuring sinkers which, therefore, will not sink the yarn between the idle needles when said sinkers advance.

The invention also includes features and combinations and arrangement of parts hereinafter described, and particularly pointed out in the appended claims.

In the accompanying drawings:

Figure 1 is a vertical sectional view of a needle cylinder of a hosiery machine, with the needles, measuring sinkers and needle beard pressers, and the supporting ring for the latter in place at one side of the cylinder, these elements being omitted at the opposite side of the cylinder.

Fig. 1^a is a view similar to Fig. 1, with idle needle shown in full lines.

Fig. 2 shows the idle needle and measuring sinker, the latter being in retracted position at the point where the yarn is about to be drawn into the fabric by the active needle.

Fig. 3 is a view of the needle.

Fig. 4 is a view of a combined measuring sinker and web holder.

Fig. 5 is a view of the needle beard presser.

In these drawings, the needle cylinder 1 may be of any ordinary construction, it being slotted for guiding the needles, and it is also slotted at its upper edge, or stitch ring portion 2, for guiding the web-holders and measuring sinkers. The needles are operated as in ordinary practice, by jacks 3 having butts 4 to engage the cams. The measuring sinkers 5 have butts 6 to be engaged by cams, as in ordinary practice, by which the sinkers are reciprocated.

The needles, which are of spring beard type, are provided with a bend or shoulder at the point *a*, this bent portion of the stem extending upwardly and inwardly in respect to the vertical axis of the needle cylinder, at an inclination. This bend or incline is

located at some distance below the needle beard, and in the normal operation of knitting its range of vertical movement is such that the stem above this beard will find a bearing on the cylinder below the upper edge of the stitch ring portion thereof.

The normal raised position of the needle for knitting is indicated at *b*, it being observed, as just stated, that the stem above this inclined shoulder is guided against the cylinder. The needle is restrained in its movement, as in ordinary practice, by spring bands 7, located in a groove 8 formed in the needle groove walls and bearing on the stems of the needles, as shown. This needle per-

forms the knitting operation substantially in the ordinary manner. When, however, these bent needles are lifted to their idle plane, which may be done, as is customary, by picks operating upon the needle butts, the idle needles will assume the position indicated at *c*. This will be due to the bend or inclined shoulder *a* of the needle stem riding over the upper edge of the cylinder at the stitch ring or edge under the pressure of the spring band or bands 7, which, pressing upon the lower portion of the needle stem,

will force the needle inwardly so that its upper portion will stand well within the normal plane of action of the needle, as indicated in dotted lines at *c*, (Fig. 1). The measuring sinker is shown in Fig. 1 in its extreme inward position, where it would sink the yarn between the needles when in the normal knitting circle represented by the needle *b*.

It will be noticed, however, that this extreme advanced position of the sinker is not far enough in towards the axis of the knitting head to sink the yarn between the needles *c*, which have been advanced or elevated to their idle plane because, as above described, these idle needles, in being elevated, have been deflected from this normal idle knitting plane inwardly to stand away from the sinkers, leaving a clearance or space at *x* for the yarn to extend through freely from the yarn guide eye to the selvage loop.

This allows the yarn to be properly taken up on the reverse or idle portion of the stroke of the needle carrier and prevents the yarn from being sunk between the idle needles, and thus liability of the yarn being cut by the sinkers on the idle needles, is avoided.

It will be noticed, however, that this extreme advanced position of the sinker is not far enough in towards the axis of the knitting head to sink the yarn between the needles *c*, which have been advanced or elevated to their idle plane because, as above

described, these idle needles, in being elevated, have been deflected from this normal idle knitting plane inwardly to stand away from the sinkers, leaving a clearance or space at *x* for the yarn to extend through freely from the yarn guide eye to the selvage loop.

This allows the yarn to be properly taken up on the reverse or idle portion of the stroke of the needle carrier and prevents the yarn from being sunk between the idle needles, and thus liability of the yarn being cut by the sinkers on the idle needles, is avoided.

It will be noticed, however, that this extreme advanced position of the sinker is not far enough in towards the axis of the knitting head to sink the yarn between the needles *c*, which have been advanced or elevated to their idle plane because, as above described, these idle needles, in being elevated, have been deflected from this normal idle knitting plane inwardly to stand away from the sinkers, leaving a clearance or space at *x* for the yarn to extend through freely from the yarn guide eye to the selvage loop.

The inward deflection of the needle will be due to the pull of the fabric as well as to the pressure from the spring bands.

I show, in Fig. 2, the relation of the measuring sinker and the leading idle needle at the knitting point where the yarn is drawn into the fabric by the active needle and off from the nose of the sinker. This sinker is in retracted position and its nose lies 10 slightly inside the circle defined by the outer faces of that portion of the needle stems lying at or below the bend thereof, or, in other words, the sinker is retracted at this point just far enough to allow the yarn for the new loop to be drawn down across its nose without straining. From the selvage loop the yarn now extends to the yarn guide through the space α between the head portion 15 of the sinker and the part of the deflected needles above the bend or shoulder, and despite the fact that it lies in front of those sinkers which are advanced in the region between the stitch point and the yarn guide, these sinkers will not bend it between 20 the stems of the idle needles because the latter stand deflected inwardly, as above stated. Nor will sinking take place on the idle needles on the reverse stroke.

On each stroke of the machine in either 25 direction, a needle is added to the idle set by being picked up to its idle plane in substantially the ordinary manner, excepting that this needle in the present invention, in joining the idle set is deflected inwardly, as 30 described, at an inclination at its upper end. Its inclined bend or shoulder, when raised to this idle position, has its lower end substantially in the horizontal plane of the nose of the sinker so that as the yarn extending 35 from the selvage loop wraps around this idle needle, on its passage by the yarn feeding point, it will lay over this shoulder and extend back to the yarn feed eye and in front of the measuring sinkers, so that as 40 the active needles, which are in the normal needle circle, approach the stitch point and with the sinkers advancing in the region between 45 the stitch point and the yarn feed eye, the yarn will be bent or sunk between 50 these active needles, the yarn resting in the notch of the sinker head 9 during this sinking action and during the pressing of the needle beards. This action just described, of 55 the yarn wrapping around the trailing idle needle, will define the line of, and make, a straight gore, the yarn being prevented from becoming trapped under the nose of the sinker, but always wrapping around the trailing idle needle. At the yarn feed finger 60 the sinkers are retracted to afford a free space for the reversal of the direction of the

yarn leading off from the guide eye, first on one side and then on the other, as the machine reciprocates.

The measuring sinker and web holder are 65 shown in one piece, but I do not limit myself in this particular.

I claim:—

1. In a circular knitting machine for making hosiery, measuring sinkers, needles having bent portions or shoulders in their stems which, when the needles are elevated to their idle plane in the formation of heel and toe work, will ride over the upper edge 70 of the needle cylinder to assume a position within the normal needle circle and out of the range of the sinkers, thus to prevent the yarn from being sunk between these idle needles, substantially as described.

2. In a circular knitting machine for 75 making hosiery, measuring sinkers, needles having bent portions or shoulders in their stems which, when the needles are elevated to their idle plane in the formation of heel and toe work, will ride over the upper edge 80 of the needle cylinder to assume a position within the normal needle circle and out of the range of the sinkers, thus to prevent the yarn from being sunk between these idle needles, and a spring band for exerting pressure 85 upon the needle stem in a direction towards the center of the machine, substantially as described.

3. In a circular knitting machine for 90 making hosiery, measuring sinkers, needles having bent portions or shoulders in their stems which, when the needles are elevated to their idle plane in the formation of heel and toe work, will ride over the upper edge 95 of the needle cylinder to assume a position within the normal needle circle and out of the range of the sinkers, thus to prevent the yarn from being sunk between these idle needles, the sinker when retracted, having its nose at, or slightly within, the circle defined by the portion of the stems of the idle needles lying at the lower ends of the shoulders or bent portions, substantially as described.

4. In a circular knitting machine for 100 making hosiery, a needle cylinder, needles adapted to be deflected radially inwardly within the normal needle circle when elevated to idle position in the making of the heel and toe, and means for so deflecting the 105 said needles when in said idle position to be out of range of the sinkers, thus to prevent the yarn from being sunk between these idle needles, substantially as described.

In testimony whereof, I affix my signature.

KENNETH HOWIE.
